(57) **CLAIM**

The ornamental design for a flagpole bracket, as shown and described.

DESCRIPTION

FIG. 1 is a perspective view of a flagpole bracket showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a cross-sectional view thereof, taken along lines 9-9 in FIG. 3.

The broken lines in FIGS. 1 through 7 represent portions of the flagpole bracket that form no part of the claimed design. The other broken lines in FIG. 3 represent cross sectional indicia only and form no part of the claimed design.

1 Claim, 9 Drawing Sheets
